UNITED STATES PATENT OFFICE.

JACOB EDSON, OF BOSTON, MASSACHUSETTS.

DIAPHRAGM SHIP'S PUMP.

SPECIFICATION forming part of Letters Patent No. 234,551, dated November 16, 1880.

Application filed July 16, 1880. (No model.)

To all whom it may concern:

Be it known that I, JACOB EDSON, a citizen of the United States, residing at Boston, in the county of Suffolk and State of Massachusetts, have invented certain new and useful Improvements in Diaphragm Ships' Pumps; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

This invention relates to improvements in diaphragm ships' pumps; and it consists in the construction, arrangement, and combination of parts, as will hereinafter be more fully shown and described, reference being had to the accompanying drawings, on which—

Figure 1 represents a plan view of my improved pump. Fig. 2 represents a sectional side elevation. Fig. 3 represents a vertical section on the line A B, shown in Fig. 1. Fig. 4 represents a cross-section on the line C D, also shown in Fig. 1. Fig. 5 represents a plan view of the base or chamber, showing the diaphragm and piston as being removed, and Fig. 6 represents a bottom view of the piston.

Similar letters refer to similar parts wherever they occur on the different parts of the drawings.

a is the base of the pump, which is secured to the deck of the vessel by means of suitable screws. Said base *a* projects downward, has a chamber, *a'*, that communicates with the bilge of the vessel by means of the suction-pipe *a''*, the upper end of the latter being for this purpose screwed into a screw-threaded recess in the center of the chamber *a'*, or otherwise secured thereto in a suitable or equivalent manner.

b represents the head and lever supporter for the pump, between the under side of which and the upper edge of the base *a* is secured the elastic rubber diaphragm *c*, as shown. *d d* are the holding-bolts for securing the head *b*, base *a*, and rubber diaphragm *c* together.

The upper part of the base *a* projects inward as a conical or convex supporting-ring, *a'''*, for the elastic rubber diaphragm *c*, which sup-

porting-ring is provided with a series of annular grooves, *a^{iv}* *a^{iv}*, and annular bars or projections *a^v* *a^v*, as well as with radial grooves *a^{vi}* *a^{vi}*, as shown. By so constructing the supporting-surface *a'''* for the elastic rubber diaphragm *c* the latter is prevented from undue strain, tension, and wear during its up-and-down-reciprocating motion, as each of the successive annular rings or bars *a^v* *a^v* serves to hold the elastic rubber diaphragm in its proper and natural position without allowing it to slip off its supporting-surface. The radial grooves *a^{vi}* *a^{vi}* serve to allow the water within the chamber *a'* to reach the annular grooves *a^{iv}* *a^{iv}*, and thus to aid in the gradual and automatical release of the elastic rubber diaphragm *c* during the upward stroke of the piston-head, and thus to prevent its cohesion to the supporting ring or surface *a'''*, as well as to hold it onto the rings or bars *a^v* *a^v* by the force required to lift the water.

e is the reciprocating annular piston, located on the upper side of the elastic rubber diaphragm *c*, as shown, below which is arranged the annular conical or convex supporting-ring *e'*, having annular rings or bars *e''* *e''*, annular grooves *e'''* *e'''*, and radial grooves *e^{iv}* *e^{iv}*, in a similar manner and for a similar purpose as heretofore described in relation to the construction and operation of the stationary supporting-surface *a'''*.

e^v *e^v* are hollow vertical ports, projecting upward from the annular piston *e*, on the top of which rests the cross-head *f*, the latter being secured to the said uprights *e^v* *e^v*, the piston *e*, diaphragm *c*, and supporting-ring *e'* by means of the screw-bolts *g g* and their nuts *g'* *g''*, as shown.

The rubber diaphragm *c* is molded to an ~ 90 form, as shown, by which it is adapted to fit the convex bearing-surfaces *a'''* *e'* when the pump is at rest, as represented in Figs. 3 and 4, and by molding the diaphragm in such a manner it is more readily adapted to the various positions of the reciprocating piston during its up-and-down motion without undue strain and wear.

The inner edge of the diaphragm *c* projects slightly upward as an annular projecting ring, *c'*, that serves as a seat for the lift-valve *h*.

c'' *c''* are annular conical projections on the

upper side of the molded double diaphragm c , and serving as packing-rings at the junction of the holding-bolts g and the hollow uprights e^v e^v , as shown in Fig. 4.

5 h is the lift-valve, having its seat on the annular rubber ring c' , and i is the suction-valve, having its seat on the upper end of the suction-pipe a'' , as shown, for the purpose of utilizing the smallest amount of space possible between the said valves, as well as for the purpose of making them self-adjustable onto their seats and in their proper relations one to another during the action of the pump. I construct them as follows: The lift-valve h is provided 10 on its under side with a central and conical recess, h' , which, in combination with the conical projection i' on the top of the suction-valve i , serves to automatically adjust the lift-valve h onto its seat; and to still further effect this 15 purpose the suction-valve i is provided with a conic frustum, i'' , acting conjointly with the inclined projections h'' h'' on the under side of the lift-valve h , as shown.

20 i''' is a cup or recess at the top of the suction-valve i , that serves to retain grit and impurities that are pumped up through the suction-pipe, and thereby to prevent the proper closing of the valve on its seat.

25 The conical projection i' on the upper part 30 of the suction-valve i is provided with a perforation, i^v , large enough to allow one or more fingers of the hand to be inserted in case it is required to remove the said valve or lift it from its seat to empty the valve-chamber, or for any 35 other purpose. i^v is a secondary and smaller hole above the perforation i^v in the conical projection i' , through which a hook or wire can be inserted to raise the valve when desired.

40 h''' is an annular cup or recess on the upper side of the lift-valve h , which cup or recess serves to retain water, which, as the valve is slightly tipped to one side during its up-and-down motion, is made to overflow, and thereby 45 to lubricate the said valve and to make it fit more closely on its seat. I make the said lift-valve h as light as possible, so that it can be raised with a minimum of power; and to insure its quick closing, and to provide a stop against 50 which it will strike when raised to its fullest extent, I use a device as follows: On the cross-head f is hung loosely the valve-stop k , that is provided with a slot-hole, k' , in its upper end, where it embraces the cross-head f , so that it 55 will serve as a stop when the central projection, h^v , on the upper side of the lift-valve h is brought to bear against the under side of said valve-stop during the upward motion of said lift-valve, and in this manner the said piece k 60 answers the purpose to act as a stop for the lift-valve h .

65 k'' is a semicircular side extension on the piece k , which is arranged to embrace one of the uprights e^v , by which the latter is made to serve as a guide for the piece k . The latter is cast in two halves, that are secured together by means of the set-screw k''' .

The head b is provided on one side with a nose or delivery-place, b' , as shown, and upon the upper side of said nose are two projections, b'' b'' , made, as shown, for the purpose of securing to the nose b' , by means of a cord or wire, &c., a suitable hose, so as to conduct the water over the deck without soiling it, or for any other purpose, as may be required.

70 The cross-head f is provided midway between its ends with two concentric circular surfaces, f' and f'' , the former a smaller one, and adapted as a lifting-support for the lever l , which is for this purpose provided with a 80 recess, l' , fitting around a portion of the circular surface f' . The extreme inner end of the lever l is curved upward, as a lip, l'' , that rests on the top of the larger circular surface f'' on the cross-head f , by which the piston is 85 forced downward during the downstroke of the lever. By this peculiar connection between the lever and its cross-head I am able to connect and disconnect the lever very rapidly, as may be needed in case of repairs; and as the 90 rubbing-surfaces are very small, as compared with other pump-connections, a minimum of frictional resistance is to be overcome.

95 The lever l is made with a tapering socket, l''' , for the reception of the curved reversible handle m , which latter is to be used in the position as shown in full lines in Fig. 3 in case the vessel is without deck-load; but if the deck is loaded and the pump is to be used, it is only necessary to reverse the handle to the 100 position shown in dotted lines in said Fig. 3.

105 As the socketed lever l inclines toward the middle of the pump, it will be seen that no fastening device is required to attach the handle m to the socketed lever.

110 In one piece with the upper end of the socketed lever l is cast a semicircular sleeve, l^v , fitting loosely over the convex skeleton-bearing b''' , that is cast in one piece with the upper 115 rim of the head b , as shown. A slot hole or opening, b^v , is made midway on the skeleton-bearing b''' . The lever l and the bearing b''' are jointed together by means of the T-headed bolt n , its head resting on the underside of the bearing b''' in the concavity, as shown, and its screw-threaded body passing through the opening b^v and up through a perforation in the semicircular sleeve l^v , on the upper side of which it is provided with a pair of nuts, n' n' , as shown.

120 A similar skeleton-bearing is cast to the rim of the head b opposite to the one marked b''' , in case it may be required to reverse the position of the lever l .

125 What I wish to secure by Letters Patent, and claim, is—

130 1. In a diaphragm-pump, the stationary supporting-surface a''' , having annular bars or projections a^v a^v , grooves a^v a^v , and radial grooves a^v a^v , and reciprocating supporting-surface e' , with its annular bars or projections e'' e'' , annular grooves e'' e'' , and radial grooves e^v e^v , combined with a flexible diaphragm, c , as and for the purpose set forth.

2. The suction-valve *i*, with its tapering top *i'*, conic frustum *i''*, combined with the lift-valve *h*, having conical recess *h'*, and inclined projections *h'' h''*, as and for the purpose set forth.

3. The suction-valve *i*, with its conical projection *i'*, provided with finger-hole *i''*, and hook-hole *i''*, as and for the purpose set forth.

4. In a diaphragm ship's pump, the piston *e*, with its ports *e'' e''*, and cross-head *f*, in combination with the lift-valve *h* and the valve-stop *k k' k''*, as and for the purpose set forth.

5. The herein-described elastic diaphragm *e*, having central opening for the lift-valve *h*, as

shown, and adapted to fit the stationary supporting-surface *a'''* when the pump-piston is at rest in its lowest position, in manner as herein set forth.

6. In combination with the cross-head *f* and its concentric surfaces *f' f''*, the lever *l*, with its recess *l'*, lip *l''*, semicircular sleeve *l'''*, and the skeleton-bearing *b'''*, with its T-headed fastening-bolt *n*, as and for the purpose set forth.

JACOB EDSON.
